OLOF OHLSON, OF NEWTON, MASSACHUSETTS, ASSIGNOR TO WALTHAM WATCH COMPANY, OF WALTHAM, MASSACHUSETTS, A CORPORATION OF MASSACHUSETTS.

COUPLING-RELEASE FOR MECHANICAL TIME-FUSES.

1,309,333.

Specification of Letters Patent.

Patented July 8, 1919.

Application filed April 23, 1918. Serial No. 230,264.

To all whom it may concern:

Be it known that I, OLOF OHLSON, a citizen of the United States, residing at Newton, in the county of Middlesex and State of Massachusetts, have invented new and useful Improvements in Coupling-Releases for Mechanical Time-Fuses, of which the following is a specification.

The present invention relates to mechanical time fuses for artillery projectiles and similar uses which include a timing member so called, a setting member, and a coupling through which the timing member may be adjusted by movement of the setting member. In instruments of this character the so called timing member is driven by a motor mechanism, such as a spring motor, an air motor driven by the wind created by the flight of the shell to which the fuse is attached, a gravity motor driven by a weight which remains relatively stationary while the shell rotates, or other motor. The fuse mechanism also includes a hammer or firing pin, or other detonating instrumentality, which is caused by a spring or other contrivance to ignite a primer when a certain part of the timing member reaches a predetermined position in the course of its travel under propulsion of the motor. The time which elapses between the firing of the shell from a gun and the detonation of the shell is determined by preliminary adjustment of the timing member which reduces or lengthens the distance it must travel under the drive of the motor to reach the position wherein it permits actuation of the hammer or firing pin. For a complete description of such a fuse, and especially the type of fuse to which I have herein illustrated my present invention as applied, reference is directed to my pending application for United States Patent Serial Number 206,278, filed December 8, 1917.

The feature with which the present invention is concerned is a means for automatically causing disconnection of the coupling through which motion is transmitted to the timing member from the setting member.

Heretofore there has been applied to mechanical time fuses a form of coupling which is carried by the setting member in the same plane with the rotatable timing member or disk and having a part entering a notch in the rim of such timing disk; such coupling being of resilient material and adapted to be

sprung out of engagement with the timing disk by centrifugal force generated by rotation of the shell. This type of coupling, in order to be sufficiently positive to insure equivalent movement of the timing disk, in either direction, with the movement of the setting member, must be very strong and stiff, wherefore it is inevitably strongly resistant to flexure. As a result the coupling will not be disengaged unless the shell has been set to spinning at a very high rate; and it has been found in practice that while a coupling of the sort described, having the necessary strength and firmness, may be thus disengaged by the centrifugal force generated by the spinning of a shell of small caliber propelled at high velocity, the force generated by the much slower rate of spinning of large caliber shells is not sufficient to cause this disengagement. It is essential, of course, that the timing disk should be disengaged from the coupling in order that it may be driven by the motor.

The purpose of my invention is to provide in connection with a coupling of the general character herein described, a means which will automatically cause it to become disconnected as soon as the projectile is fired, and regardless of the rate of rotation at which the projectile is caused to spin. Briefly stated the essential feature of the invention comprises a coupling which is under stress, or is adapted to be put under stress, tending to cause its disengagement from one of the two elements constituted by the setting member and the timing member, and a retainer which normally holds it in secure engagement with that member from which it is disengageable, such retainer being rendered inoperative for this purpose by force set into action when the shell is fired.

In the drawings wherein I have illustrated a satisfactory embodiment of the invention, Figure 1 is an elevation of an entire time fuse containing such invention.

Fig. 2 is a cross section on line 2—2 of Fig. 1 and a plan of the parts lying below such line.

Fig. 3 is a cross section of the setting member taken on line 3—3 of Fig. 2, and it represents in elevation the features of my invention which are new in the combination here illustrated.

Fig. 4 is a view similar to Fig. 3 showing the movable parts represented therein as

100

105

110

occupying a different position from that shown in Fig. 3.

Fig. 5 is a sectional view, on a larger scale, taken on line 5—5 of Fig. 3 showing a detail.

5 Fig. 6 is a perspective view of the coupling detached from the rest of the fuse.

Figs. 7 and 8 are elevations from positions at right angles to one another of the displaceable coupling retainer.

10 The same reference characters indicate the same parts in all the figures.

Referring to the drawings 10 represents the base of the fuse which is constructed so that it may be mounted on the tip end of a 15 projectile. 11 is the part which for the purposes of this description I have called the setting member, the same being a ring or annulus coaxial with the base and mounted thereon in a manner permitting it to be 20 turned about its axis, preferably in the manner illustrated more in detail in my pending application Serial Number 210,494 filed January 5, 1918. This setting member has external graduations for showing the extent of its adjustments 12 represents a cap mounted on the setting member and being of substantially conical form. Referring to Fig. 2, 13 represents the timing member, which is here shown as a disk and will be 30 hereinafter so called, the same being mounted on a staff 14 driven by a spring motor, and being adjustable about said staff. This timing disk has a notch 15 in its periphery which, when it arrives opposite to 35 a finger 16 on a release lever 17, allows the firing pin or hammer to operate, in a manner preferably such as that shown in my application Serial Number 206,278, previously referred to. When driven by the 40 motor, the timing disk rotates in the direction of the arrow, and the time from the moment of firing to the moment of detonation is determined by the extent of the angle from notch 15 in this direction to the finger 45 16; and the degree of the angle may be varied by adjustment of the disk through turning the setting member 11. Adjusting movements of the setting member are transmitted to the timing disk by a coupling 18, 50 here shown as a spring strip rigidly secured at one end by fastenings 19 to an internal surface of the setting member, and having on its free end a tongue 20 which enters a notch 21 in the rim of the timing disk at 55 such an abrupt angle to the circumference of the same that it is effective to move the timing disk in either direction when the setting member is correspondingly turned.

This coupling therefore is connected to 60 one of the members constituted by the setting member and the timing disk, in a permanent manner, and is engaged with the other of these members in a disengageable manner. It may be disengaged by withdrawing its tongue 20 from the notch 21 far

enough to permit the timing disk to rotate in the direction of the arrow.

Instead of being so formed as normally to be held by its own strength in engagement with the timing disk, and being disengaged therefrom by centrifugal force, as is the case with types of coupling heretofore known, this coupling 18 is preferably formed with a permanent set which tends to cause its free end to lie against the inner surface of the setting ring, or at least to occupy a position wherein the tongue 20 is withdrawn from the notch 21 far enough to permit the timing disk to turn. It requires exertion of material force to shift the coupling into engagement with the timing disk in the position which it is shown as occupying in Figs. 2, 3, and 5. When placed in this coupled position, the coupling is there retained by a retainer 22, here shown as a finger pivoted on a fulcrum pin 23 which is mounted on the setting ring near the free end of the coupling, so that its end may pass between the latter and the adjacent surface of the ring when the coupling is engaged as described. This retainer has also an arm 24 projecting from the opposite side of its fulcrum from the finger 22 and being of such mass, and its center of gravity so located that it far overbalances the finger 22. When the finger is in the operative position where it retains the coupling as described, this overbalancing arm is raised above the upper surface of a rib 25 formed on the interior of the setting ring, 100 as shown in Fig. 3. The arm 24 is so formed as to its outer surface that it may turn about the axis 23 freely within the surrounding wall of the setting ring. I may state that as a desirable detail of manufacture, the outer surface of this arm is made with a spherical curvature, that is as the segment of a sphere having the same radius as the adjacent surface of the setting ring and its center in the axis of this ring 110 and in line with the axis of the pivot 23; whereby the arm is enabled to fit closely against the adjacent surface of the ring 11 and also to turn freely, as described.

The finger 22 is beveled on the side next 115 to the coupling so as to form a wedge 26 which enters a groove 27 in the outer side of the coupling and engages a complementally inclined surface on the latter. These complementally inclined surfaces are provided to hold the retainer in the operative position shown in Fig. 3 and prevent it from becoming disengaged and rendered inoperative by the ordinary shocks occurring in handling the shell or accidentally dropping it, that is, by shocks substantially less severe than that which results from firing.

When the shell is fired the great force of set back, due to inertia under the shock of firing acting on the overbalancing arm 24 130

withdraws the finger 22 from the path of outward movement of the free end of the coupling, overcoming the yielding resistance caused by the spring tension of the coupling 5 pressing the overlapping inclined surface of the recess 27 against the inclined side of wedge 26. When thus withdrawn, the retainer finger becomes inoperative and the coupling thereupon springs by its own resilience, and independently of centrifugal force, out of the notch 21, leaving the timing disk free to be rotated at the predetermined rate by the driving mechanism.

This disengagement of the coupling is 15 certain whatever the speed of rotation of the shell may be, whether it is a high velocity small caliber shell or a larger caliber shell of the same or lower velocity, which spins at a slower rate than the small caliber shell; 20 and disengagement of the retainer, which permits this disengagement of the coupling, is altogether automatic and is effected by the force of set back.

The purpose of the retainer 22 is to hold 25 the disengageable coupling in secure engagement with the member from which it is disengageable, whereby such coupling is made certainly effective to transmit adjusting movements in either direction, overcom- 30 ing the more or less considerable frictional resistance to movement of the timing member about its driving staff 14; and to leave the coupling free to be disengaged when withdrawn or displaced, and so disabled for 35 its holding function, by set back. This purpose is likewise served when the retainer is used in connection with a coupling which is not under stress tending always to disengage it but is resiliently held in engagement and 40 is of such easily flexible character, or otherwise so lightly held, that it may be disengaged by centrifugal force of relatively low intensity and so may not be in itself so stiff or rigid as is necessary for effecting adjust- 45 ments of the timing member under all conditions. Therefore I do not necessarily limit the present invention to the combination with a coupling under stress tending constantly to become disengaged, but in- 50 clude within my claim to protection a retainer for the purpose indicated in connection with a coupling of any character with which it may be used, between an adjustable timing member and a setting member. 55 Neither do I limit such claim to a retainer for this purpose which is movable by set back only, instead of by other forces operating when the shell is fired, or to one which is moved angularly about a pivot; but in- 60 clude a retainer of any form movable in any manner and having essentially the purpose, function, and result set forth.

What I claim and desire to secure by Letters Patent is:

65 1. The combination in a time fuse with

an adjustable timing member, an adjustable setting member, and a coupling between said members under stress constantly tending to cause its disengagement from one of them, of a retainer for holding said coupling in 70 engagement with such member, said retainer being arranged to release the coupling upon firing of the projectile to which the fuse is attached from a gun.

2. The combination as set forth in claim 75 1 distinguished by the fact that said retainer normally bears upon the coupling and is displaced from its position of bearing by forces set up upon firing.

3. The combination in a time fuse as set 80 forth in claim 1 distinguished by the fact that said retainer is moved by set back so as thus to release the coupling.

4. The combination in a time fuse as claimed in claim 1 distinguished by the fact 85 that said retainer is provided with a finger normally bearing on the side of the coupling away from the member with which it is thus detachably engaged, and is adapted to be withdrawn from the path of that part of the 90 coupling on which it so bears.

5. In a time fuse the combination with a rotatable and adjustable timing disk, a setting ring surrounding said disk and being rotatably adjustable, and a coupling carried 95 by said ring and having a part engaged with said disk, such part being constantly urged out of engagement with the disk, of a retainer carried by the setting ring having a finger adapted to be inserted between the 100 ring and that part of the coupling which engages the timing disk, and arranged to be withdrawn by inertia under the shock of firing.

6. In a time fuse the combination with a 105 rotatable timing member and a substantially coaxial setting ring, of a coupling consisting of a spring strip secured at one end to said setting ring and having its free end formed to engage and withdraw from a part 110 of said timing member, said free end being under stress tending always to withdraw it from such engagement, and a retainer mounted movably on the setting ring having a finger adapted to hold the movable part 115 of said spring strip in engagement with the timing member, and a weighted part movable by its inertia under the shock of firing so as to withdraw said finger from the position in which it thus holds the coupling 120 strip.

7. A time fuse combination as claimed in claim 6 distinguished by the fact that the finger and coupling strip have coacting wedge portions arranged to prevent such 125 withdrawal of the finger by shocks materially less severe than that applied in firing.

8. A time fuse having in combination a timing member, a setting member, a disengageable coupling between said members 130

- adapted to transmit movements from the setting member to the timing member, whereby the latter may be adjusted, and a retainer for holding said coupling engaged and being movably mounted to be withdrawn independently of the coupling from holding position upon firing from a gun, whereby the coupling is left free to become disengaged.
9. A time fuse having in combination a timing member, a setting member, a disengageable coupling between them adapted to transmit movements from the setting member to the timing member, whereby the latter may be adjusted, and a retainer for holding said coupling engaged and being movably mounted to be withdrawn independently of movement of the coupling from holding position by its inertia under the shock of firing, the coupling and retainer having resiliently contacting overlapping shoulders arranged to resist withdrawal of the retainer by shocks of materially less intensity than that of firing.
10. A time fuse having in combination an adjustable timing member, a motor for driving the same, a setting member, a coupling permanently connected to the setting member and engageable in a separable manner with the timing member, so formed as to that part which engages the latter that it is able to transmit adjusting movements from the setting to the timing member when so engaged, and a retainer mounted with a part so engaging the coupling as to hold it securely in engagement with the timing

member and being movable independently of movement of the coupling by force acting when the projectile to which the fuse is attached is fired from a gun to withdraw said part from such engagement with the coupling.

11. A time fuse having in combination an adjustable timing member, a motor for driving the same, a setting member, a coupling permanently connected to the setting member and engageable in a separable manner with the timing member, so formed as to that part which engages the latter that it is able to transmit adjusting movements from the setting to the timing member when so engaged, and a retainer mounted with a part so engaging the coupling as to hold it securely in engagement with the timing member and being movable by force acting when the projectile to which the fuse is attached is fired from a gun to withdraw said part from such engagement with the coupling, the engaging parts of the retainer and coupling being overlapped across and inclined to the path in which said retainer part moves in withdrawing, and one of said parts being constructed and arranged to yield and permit such withdrawal by the action of such force, but preventing such withdrawal under application of forces of materially less intensity.

In testimony whereof I have affixed my signature.

OLOF OHLSON.
